UNITED STATES PATENT OFFICE.

EDWARD F. CHAFFEE, OF SYRACUSE, NEW YORK, ASSIGNEE TO OLIVER M. EDWARDS,
OF SYRACUSE, NEW YORK.

TRAP-DOOR FOR RAILWAY-CARS AND SIMILAR STRUCTURES.

1,174,119.

Specification of Letters Patent.

Patented Mar. 7, 1916.

Application filed October 6, 1910. Serial No. 585,703.

To all whom it may concern:

Be it known that I, EDWARD F. CHAFFEE, a citizen of the United States, residing at Syracuse, county of Onondaga, State of New York, have invented certain new and useful Improvements in Trap-Doors for Railway-Cars and Similar Structures, of which the following is a full, clear, and exact description, reference being had to the drawings accompanying the same.

This invention relates generally to "trap doors" for railway cars and similar structures, as for instance such as are used to cover and uncover the steps leading to and from the platforms of passenger cars, but more particularly to "trap doors," where there is a space between the platforms of cars and the station platform, which it is desirable to cover or bridge over to prevent passengers and others from stepping into such space and being injured thereby.

One of the objects of this invention is to provide a "trap door" slidable lengthwise of its axial line of hinging or sidewise of the car in which it is used and which turns on its pivotal points in opening or closing a given space in the platform or platforms.

Another object is to provide simple and easily operable means for automatically projecting and retracting the door lengthwise of its axial line of hinging by the act of turning it on the axial line of the hinging means from one position to another and back again.

Another object is to provide a simple and reliable means for moving a "trap door" lengthwise of its axial line of hinging or sidewise of the car during the act of closing the same and thereby bridging over a space between the station and car platforms.

Another object is to provide means for moving a "trap door" beyond the edge of the platform in which it is mounted by a change in positions, one relatively to the other, of the points of attachment of such means of the door and platform.

Other objects will appear from the description hereinafter given.

With these objects in view the invention consists in the construction, combination and arrangement of parts to be hereinafter more fully described and particularly pointed out in the claims hereunto annexed and forming a part of this specification.

It has been found in practice that many

times it is necessary to locate some stations at points where the tracks are more or less curved. In such cases that station platform has to be constructed farther away from the track than is the case where the track is straight in order that the projecting ends of the cars shall properly pass by such platforms. This necessarily leaves more or less space between the cars and the station platforms which is dangerous and liable to cause accidents to persons in leaving or entering the cars. It has also been found that at some stations it is very desirable to have the platform on substantially the same level as the car platform, while at other stations on the same line the platforms are arranged on suitable levels for use with the ordinary steps commonly in use on railway cars.

In the use of ordinary railway cars with differing levels of platforms at the stations along the line, it has been found desirable to use "trap doors" such as are commonly used in wide vestibule trains for covering and uncovering the steps ordinarily used for the ingress and egress of passengers at such stations on the line which are located at points where the tracks are curved and to project or move sidewise such doors beyond the points where the cars stand at the platforms of such stations and thereby bridge over the space between the platforms of the cars and the stations and thus provide safe and proper passage for passengers in leaving or entering the cars.

Figure 1 shows in plan view a trap door and a portion of a car platform illustrating generally the door when in position for use to bridge over a given space between a car and station platform, with the means by which the door is projected sidewise of the car or lengthwise of its axial line of hinging, which means is seen in dotted lines. Fig. 2 shows an edge view of that which is seen in Fig. 1. Fig. 3 shows a portion of the door in the position it occupies in the open position, or as seen when looking into the interior of the car from the end thereof, the means by which the door is projected and retracted being seen in full lines. Fig. 4 shows on an enlarged scale a cross section of the door hinge illustrating an arrangement of parts by which it is moved lengthwise of its axial line of hinging the same in the platform of the car. Fig. 5 shows a

modified form of means of automatically moving the door lengthwise of its axial line of hinging and also a different form of hinging means from what is seen in preceding figures, the door being shown in the open position as when not in use bridging a space between the car and platform of the station. Fig. 6 shows a cross sectional view of that which is seen on line 6—6 of Fig. 5.

10 Like letters of reference, wherever they occur, indicate corresponding parts of the several figures of the drawings.

One embodiment of my invention is illustrated in Figs. 1 to 4, inclusive, which is the preferred form, and as there seen the door is hung in the platform A by a form of hinging means, as C, well known in the art, wherein torsional springs are used to assist in opening the door, there being a sliding movement on its hinging means given to the door in addition to the turning movement heretofore common in this particular form of hinging means. As there shown the invention is applied to an ordinary open platform of a passenger car provided with the usual steps for use with low station platforms thereby adapting the car for use with platforms of substantially the same height or level as the car platform where it is desired 25 to bridge over more or less of a given space between the car and station platforms. This well known form of hinging means is shown and described in Patent #781,045, dated Feb. 7, 1905, and as there shown the 30 torsional springs are connected with the door at one end and to the platform at the other and are arranged on the axial line of the hinge pintles or pivots. Other forms of hinging means may be employed if desired, 40 such as for instance as is illustrated in Figs. 5 and 6 of the drawings, which particular form is seen in said Patent 781,045. This particular form of hinging means seen in this patent is not a material portion of the 45 present invention.

The hinging means C, as shown in Figs. 1 to 4, inclusive, consist of the above well known form which provides for giving the door the usual quarter turn to close or open 50 it in use and means for permitting the door to move lengthwise of the axial line of its hinging means or sidewise of the car and yet maintain operative connection between the torsional spring or springs and the door. 55 This is accomplished, as shown, by forming such hinge in two parts, as c and c', which parts are constructed so that one may be received by the other and there is an endwise movement of one part relatively to the other, but the two parts turn as a single part would turn in moving the door from one position to the other. As thus shown the part c is fixedly secured to the main portion of the door and is shorter in length 60 than is the part c' to which the torsional

spring or springs are attached. This part c' is given a shape substantially that of the interior of the part c in which it is received and is connected to the main portion of the door by being received within the part c and the two parts turn as the main portion of the door turns and such main portion with the part c attached thereto can move endwise on the part c' to the extent that the part c is shorter than the part c', as seen in Figs. 1 and 3. The means, as D, by which such endwise movement is given to the part c and consequently to the door B to which such part of the hinging means is secured relatively to the part c', consists, as thus shown, of the bar or piece d, Figs. 2 and 3, having at each end the ball member of a ball and socket joint, as d', the other member of such joint being constructed to receive its respective ball on the bar as d. One socket member of such means is attached to the main portion of the door, as seen in Figs. 1, 2 and 3 of the drawings and the other member is attached to the platform or other convenient portion of the car in which the door is to be used. The bar d of the moving means, as D, is preferably formed as shown, but it may be otherwise formed if desired. The ball and socket joint or connections, as d', are the preferred form of means of connecting the moving means to the door and car but any form of connection which will permit of substantially the same mode of operation which is herein set forth will be 95 the equivalent of the form herein shown in Figs. 1 to 4, inclusive.

The manner of combining the means, as D, seen in these Figs. 1 to 4, inclusive, with the door and platform is such that as the 105 door is turned on its hinging means from the position seen in Fig. 3 to that shown in Figs. 1 and 2 the end of the bar d which is attached to the door B, describes the arc of a circle whose center is the other end of that bar, which is, as shown, secured to the platform of the car. As a result the end of the bar d attached to the door forces the door to move lengthwise of its hinging means from the position seen in Fig. 3 to that seen 110 in Fig. 1, where such door is projected out from the side of the car quite a considerable distance. When the door is turned back or its direction of movement is reversed the part d moves in the same arc of the circle 120 in which it previously moved and pulls the door back from the position seen in Fig. 1 to that seen in Fig. 3. It is to be observed that the nearer that the pivotal points d' approach a vertical line, when the door is 125 in the position seen in Fig. 3, the greater will be the sliding movement of the door upon its hinging means and the greater will be the projection of the door sidewise of the car.

A modified form of hinging means C' and means for moving the door B lengthwise of the axial line of its hinging means, as D', are seen in Figs. 5 and 6 and as there shown 5 the door B is hinged to the platform A of the car by suitable members, as c³, attached to the platform which receives the ends of a rod c⁴ which is secured as shown fixedly to such members and the female members 10 c⁵ attached to the door and which turn and slide upon the rod c⁴ as the door is moved from one position to another. The means, as D', by which the door B is moved lengthwise of its axial line of hinging to the plat- 15 form A consists of a lever d³ one end of which is pivotally secured to the door B at x and the other is connected with a worm d⁴ and nut d⁵ mounted upon the rod c⁴ at x'. This lever d³ is fulcrumed at y to a part 20 d⁶ which is mounted upon the rod c⁴ and turns thereon as the door B moves from the open to the closed and projected position, but is prevented from moving endwise of the rod c⁴ by the collars, as d⁷, secured to 25 the rod c⁴ on each side of the part d⁶. As a result the door, as it moves from the open or retracted position seen in Figs. 5 and 6, toward the closed or projected position for use, the lever d³ cannot move at the point v 30 in an endwise direction relatively to the rod c⁴ and the nut d⁵ necessarily turns on the worm or screw d⁴ mounted on the shaft or rod c⁴ a short distance equal to about a quarter turn or revolution of the door and 35 the door is forced to move endwise of the rod c⁴ and the part d⁶ connected therewith during the entire extent of the movement of the door in the closing or projected direction, thus bringing those parts c⁵ of the 40 hinging means and the door to which they are attached into position for the projecting portion of the door, seen at the right of Fig. 5, into position to pass down and form a continuation of the part of the plat- 45 form as a' when the door is fully closed or moved into its fully projected position.

In each of the constructions here shown the projecting means is so connected with the door and platform that the door is projected or moved lengthwise of its axial line of hinging as the door is being turned from the open to the closed position, the door having a combined turning and sidewise sliding movement on its hinging means. As 50 a result of this combined or compound movement the door is automatically projected or retracted in the act of turning it on its hinging means.

It will be observed that in each construction here shown the hinging means is so formed that the door can turn independently of the sidewise sliding movement or movement lengthwise of the axial line of such hinging means and vice versa. It will 60 also be observed that in each case the means

for moving the trap door lengthwise of the axial line of the hinging means is attached to the door some distance away from the edges thereof and to the platform within the space to be covered by the door when in 70 the closed position; also that such means, when the door is in the open position, occupies but little of such space outside of the hinging means and hence, does not materially interfere with the egress and ingress of those using the car platform. This 75 form of hinging means is adapted for use with other specific forms of projecting and retracting means, whether the latter means is combined with the door and platform as 80 here shown or in any other manner that the constructor sees fit to employ.

What is herein shown and described will naturally suggest to those skilled in the art other specific forms of means for giving to 85 the trap door a sidewise and turning movement and means for projecting and retracting the door to bridge over or cover a space between the car and station platforms and modifications of that which is herein shown 90 and described which, while varying in form or details of construction or arrangement will have substantially the same method or mode of operation in accomplishing essentially the same work as is the case with that 95 which is herein set forth, hence, I do not desire to limit my invention to the specific forms, constructions or arrangements of parts or devices herein shown and described but desire to include all forms, constructions 100 and arrangements that are within the spirit of my invention.

What I claim as new is:

1. A trap door of the character described provided with means for hinging it in place 105 to close an opening, which means is constructed in two parts one of which is secured to the main portion of the door and is adapted to engage with the other and slidably move lengthwise of the axial line 110 of the hinging means, which other part is adapted to be mounted in place and engage with the first mentioned part to hold the two in position relatively to one another during the turning and sliding movements 115 of the door upon the hinging means, substantially as set forth.

2. A trap door of the character described provided with means for hinging it in place 120 to close an opening which means is constructed in two parts one of which is adapted to receive and hold the other against turning thereon while permitting it to move endwise of the axial line of such means and the other part is adapted to be mounted in 125 place to engage with the first mentioned part and permit the door to move in two directions, substantially as set forth.

3. A trap door of the character described provided with means for hinging it in place 130

to close an opening which means is constructed in two parts one of which is adapted to be secured to the door and receive the other part and permit of an endwise movement of one relatively to the other and a second part adapted to engage with the first mentioned part and permit it to turn on the axial line of such means, substantially as set forth.

4. A trap door of the character described provided with means for hinging it in place to close an opening, which means is adapted to permit the door to move lengthwise of the axial line of such means and to turn thereon, and means adapted to be connected to the door and platform underneath the tread surfaces of the same and when so connected to automatically move the door lengthwise of the axial line of the hinging means and to turn the door thereon, substantially as set forth.

5. A trap door of the character described provided with means for hinging it in place to close an opening, which means is adapted to permit the door to move lengthwise of the axial line of such means and to turn thereon, and means adapted to be connected to the door underneath the same away from the edges thereof and to the platform, one portion of which is movable in different directions relatively to another and when so connected to automatically move the door lengthwise of the axial line of the hinging means to close such opening and to turn the door thereon, substantially as set forth.

6. A trap door of the character described provided with means for hinging it in place to close an opening, which means is adapted to permit the door to move lengthwise of the axial line of such means, and means adapted to be connected to the under side of the door and to the platform by a universal joint which permits one portion of such means to move in different directions relatively to the other portions and such axial line, which means, when so connected, is adapted to move the door lengthwise of the axial line of the hinging means, substantially as set forth.

7. A trap door of the character described provided with means for hinging it in place to close an opening of less dimension in one direction than the door itself, which means is adapted to permit the door to move lengthwise of the axial line of such means, and means adapted to be connected to the door at a distance from the edges thereof and to the platform by ball and socket joints and when so connected to automatically move the door lengthwise of the axial line of the hinging means, substantially as set forth.

8. In a car platform the combination, substantially as set forth, of an opening 65 therein, a door of greater dimensions than

the opening for closing the same, and hinging means in two parts for hanging the door in the platform to close such opening and permit the door to move endwise of the axial line of the hinging means. 70

9. In a car platform the combination, substantially as set forth, of an opening therein, a door of larger dimensions than such opening, and hinging means for hanging the door in the platform and to turn thereon 75 and move lengthwise of the axial line of such means and close such opening as the door is so moved.

10. In a car platform the combination, substantially as set forth, of an opening 80 therein, a door of larger dimensions than such opening, hinging means adapted to hang the door in the platform and to turn and slide thereon, and means connected with the door and platform adapted to project 85 the door lengthwise of the axial line of the hinging means and cover the opening in the platform.

11. In a car platform the combination, substantially as set forth, of an opening 90 therein, a door of larger dimensions than such opening, hinging means adapted to hang the door in the platform with a side- 95 wise sliding movement as the door turns to open or close, and means connected with the door and platform adapted to project such door sidewise and cover the opening in the platform as it turns on its hinging means.

12. In a car platform the combination, 100 substantially as set forth, of an opening therein, a door for closing such opening, hinging means for hanging the door in the platform with a compound movement, and means adapted to be arranged within the 105 space to be covered by the door to move it lengthwise of the axial line of hinging it to the platform in closing the opening therein.

13. In a car platform the combination, 110 substantially as set forth, of an opening therein, a door of greater dimensions than the opening for closing the same, hinging means for hanging the door in the platform with a turning and sliding movement, 115 and means connecting with the platform and to the underside of the door adapted to automatically move the door lengthwise of its axial line of hinging to the platform as the door turns in closing the opening therein. 120

14. In a car platform the combination, substantially as set forth, of an opening therein, a door for closing such opening, hinging means adapted to permit the door to have a compound movement in the opening and closing of such opening, and means adapted to automatically move the door lengthwise of the axial line of the hinging means as the door turns to open or close such opening in the platform. 125

15. In a car platform the combination, substantially as set forth, of an opening therein, a door for closing such opening, hinging means adapted to permit the door to have a compound movement in opening and closing such opening, and means connecting directly with the underside of the door and to the platform with a connection permitting one portion of such means to move relatively to the hinging means and adapted to automatically move the door lengthwise of the axial line of the hinging means as the door turns in opening or closing.

16. In a car platform the combination, substantially as set forth, of an opening therein, a door for closing such opening, hinging means adapted to permit the door to have a compound movement as it turns in opening or closing such opening, and means adapted to be connected to both the door and platform within the space to be covered by the door when closed, a portion of which means is freely movable relatively to both the door and platform and to project or retract the door as it turns on the hinging means in opening or closing.

17. In a car platform, the combination, substantially as set forth, of an opening therein, a door of larger dimensions than said opening, and hinging means for hanging the door in the platform and to turn thereon and automatically move lengthwise of the axial line of such means and close said opening as the door is so moved.

18. In a car platform, the combination of a door for covering an opening in said plat-

form, with hinging means for the door having provision for automatically moving the door lengthwise of the axial line of said hinging means on the closing of the door. 40

19. In a car platform, the combination of a door for covering an opening in said platform, with hinging means for the door having provision for automatically moving the door lengthwise of the axial line of said 45 hinging means to cause said door to project beyond the side of the car on the closing of the door and for automatically returning the door to its original position on the opening of the door. 50

20. In a car platform, the combination of a door fulcrumed thereon for covering an opening therein; and means coöperating with said door for automatically causing said door to project beyond the side of the 55 car on the closing of the door.

21. In a car platform, the combination of a door fulcrumed thereon for covering an opening therein, with means for automatically causing said door to project beyond the 60 side of the car on the closing of the door, and means tending to open said door.

22. In a car platform, the combination of a door fulcrumed thereon for covering an opening therein, with means for automatically causing said door to project beyond the 65 side of the car on the closing of the door, and spring means tending to open said door.

EDWARD F. CHAFFEE.
